WEATHER STRIP

Filed Dec. 22, 1930

UNITED STATES PATENT OFFICE

FRANK REESE, OF MINNEAPOLIS, MINNESOTA, ASSIGNOR TO REESE METAL WEATHER STRIP CO., OF MINNEAPOLIS, MINNESOTA, A CORPORATION OF MINNESOTA

WEATHER STRIP

Application filed December 22, 1930. Serial No. 503,894.

My present invention relates to weather strips for sliding window sashes commonly referred to in the trade as double-hung windows.

6 This invention provides for each side of a sliding sash a weather strip device comprising two members, one of which is applicable to the sash and the other of which is applicable to a frame in which the sash is slidably mounted. These two members are connected by interlocked elements for common movement, at their point of connection, except a longitudinal sliding movement of the sash member element in respect to the frame member element to permit the required raising and lowering movements of the sash in respect to the frame. The weather strip device is constructed and arranged for self-adjustment to permit varying changes in the relative fit 20 of the sash in the frame due to shrinkage or expansion of the sash, to the bowing of the frame or to the warping of either of the sash stiles. As is well-known changes in the moisture contents of a sash and frame, differences 25 in humidity and temperature between the outside and inside of a window, and the unskillful fitting and installation of a sash in its frame all combine to produce a constantly changing relative fit of the sash in the frame.

30 In order to make possible the use of the above method of interlocking two weather strip members, one of which is attached to a sash and the other of which is attached to the frame, it is necessary to provide two adjustments 35 on account of the above varying changes of the sash with relation to the frame.

One of these adjustments must permit the interlocked members to adjust themselves perfectly to the variations in the crack or opening between the sash and the frame caused by swelling, shrinking or fitting of the sash by a carpenter. The other of these adjustments must permit the interlocked members to adjust themselves to variations in 40 clearance between the faces of the sash and the sides of the frame channel runway in which the sash is mounted, caused usually by the warping or bowing of the sash.

The present invention provides for these 45 two adjustments, either singly or at the same

time, as well as a snug fit between the interlocked elements of the members which would be impossible without such full adjustment and at the same time avoids binding of the members and hard operation of the sash. The 55 efficiency of cooperating weather strip members depends upon the closeness of contact therebetween and upon the maintenance of tight joints at their attachment to a sash and frame, which has been accomplished in my present invention and provides a practical and lasting air and dust seal between the sash and frame. This full adjustment of a weather strip device prevents the members thereof from being loosened at their attachment with the sash and frame under strains 60 produced by shrinkage and warpage.

65 Proper installation of the weather strip device is facilitated by the novel self-adjustments of which it is capable and when once 70 installed the equipment functions properly under all conditions without getting out of order or losing its efficiency due to natural causes, heretofore enumerated.

In general, the preferred form of the 75 weather strip device, as illustrated, has the novel adjustments embodied in its frame member, but, obviously the relative lateral adjustment of the sash in respect to the frame might be embodied in the sash member instead of the frame member. However, the 80 frame construction affords greater advantages for the attachment of the weather strip member in which the several adjustments are embodied. As the required adjustment for shrinkage is greater than that for warpage the weather strip device illustrated shows greater provision for shrinkage adjustment.

To the above end, generally stated, the invention consists of the novel devices and combination of devices hereinafter described and defined in the claims.

In the accompanying drawing, which illustrates the invention, like characters indicate 85 like parts throughout the several views.

Referring to the drawing:

Fig. 1 is a fragmentary view principally in horizontal section taken on an irregular line through the upper and lower sashes and 100

frame of a double-hung window and embodying one form of the weather strip device;

Figs. 2 to 9, inclusive, are fragmentary detail views in horizontal section taken through the lower sash and frame of a double-hung window and showing still other forms of the weather strip device; and

Figs. 10 and 11 are fragmentary detail views showing different forms for the interlocked elements of the weather strip device.

The numeral 12 indicates the wooden frame of a double-hung window having an inner channel runway 13 and an outer channel runway 14 formed, respectively, by an inner stop 15 and a parting strip 16 and said strip and an outer stop 17. Said parting strip 16 is removably mounted in a groove 18 in the frame 12. A lower sash 19 and an upper sash 20 are mounted in the runways 13 and 14, respectively, for vertical sliding movement. It is important to note that the working fit of each sash in its runway is such that said sash is free for a limited lateral movement (at right angles to the plane of the sash) in said runway and a limited horizontal movement in the plane of said sash and in respect thereto.

The parts thus far described are the same in all figures illustrated and have the same reference characters. The weather strip devices for the upper and lower sashes are the same and except in Fig. 1 only the lower sash is illustrated.

All of the different forms of weather strip devices, illustrated, are capable of two distinct and important functions, aside from forming a weather-tight joint between the sash and frame, to wit; said device is self-adjusting to permit the sash to move laterally in its runway or horizontally in the plane of the sash, as will hereinafter be more fully described.

Referring first to the weather strip device, shown in Fig. 1, the same comprises a sash member or strip 21 and a frame member or strip 22. Said sash member 21 is mounted in a shallow rabbet 23 in the face of the sash 19 adjacent to the parting strip 16 and is secured by nails X to said sash. On the outer edge portion of the sash member 21 is a tubular element 24 with which the frame member 22 is interlocked, as will presently appear. This tubular element 24 extends the full length of the sash member 21 and is formed by rolling said member to substantially a full circle in which its free edge portions are spaced from the body thereof to leave a narrow longitudinal entrance passageway 25. The sash 19 is further rabbeted at 26 to receive the tubular element 24 and which element is substantially within the body of said sash.

The frame member 22 extends substantially to the full width of the runway 14 and is secured by nails X to the frame 12 adjacent to the inner stop 15. Said frame member 22

at its free edge portion is folded upon itself to form a two-ply flange 27 and a U-shaped fold 28, and which flange and fold extend perpendicular to the body of the frame member 22 and from opposite sides thereof. The flange 27 extends into the groove 18 at the adjacent face of the parting strip 16 with a working fit, and the fold 28 is substantially parallel to the sash member 21 and in opposing relation. The frame member 22, toward the terminal end of its fold 28 extends laterally and to an extent pivotally through the passageway 25, and formed therewith is a tubular element 29 telescoped in the tubular member 24 with a working fit. The interlocked elements 24 and 29 connect the sash member 21 to the frame member 22 for common movement, except free longitudinal movement of the tubular element 24 on the tubular element 29, to permit the required raising and lowering movements of the sash 19. It will be noted that the width of the passageway 25 will permit limited relative turning movement of the tubular elements 24 and 29 as required.

It is important to note that the frame member 22 extends horizontally oblique in the runway 14 between the frame 12 and sash 19 and is out of contact with both thereof for free lateral flexing movement in either direction. Obviously, the frame member 22 is self-adjusting to permit shifting movement of the sash 19 horizontally in the plane thereof. The gap in the fold 28 and the space between said fold and the sash member 21 permits further self-adjustment of the frame member 22 to permit lateral movement of the sash 19 in the runway 14.

The weather strip device for the upper sash 20 is identical with the weather strip device just described and the parts thereof have the same reference characters. Rabbets in the several illustrations of the sash 19 are designated by the same reference numerals.

In the construction shown in Fig. 2, the sash member and the frame member are designated by the numerals 30 and 31, respectively, said sash member 30 is like sash member 21 and the interlocked elements which connect the sash member 30 and the frame member 31 are like those shown in Fig. 1 and designated by the numeral 32. The frame member 31 is secured by nails X to the frame 12, between said frame and parting strip 16, and comprises a relatively long U-shaped fold 33 which extends transversely in the runway 13, a second relatively short U-shaped fold 34, which extends into the groove 18 between the anchored edge portion of the frame member 31 and has the same position as the flange 27, and a third U-shaped fold 35 which corresponds to the fold 28. Obviously, the fold 33 is self-adjusting to permit horizontal movement of

the sash 19 in its plane and in respect to the frame 12, and the fold 35 is self-adjusting to permit lateral movement of the sash 19 in the frame 12.

The weather strip device shown in Fig. 3 comprises a sash member 36 and a frame member 37, the former of which is in the form of an angle one flange of which is in the rabbet 23 and secured by nails X to the sash 19 and the other flange thereof is likewise secured to the respective edge of said sash.

Interlocked elements 38 which connect the sash member 36 and frame member 37 are identical with the structure shown in Fig. 1 with the exception that the entrance passageway is substantially at right angles to the entrance passageway 25 and faces the frame 12. The formation of the frame member 37 is quite different from that shown in Figs. 1 and 2 in that in place of a flexing or yielding movement to permit horizontal movement of the sash 19 in its plane, this movement is accomplished by a slip joint in the frame member 37. Said frame member 37 has a U-shaped fold 39 that corresponds to the fold 28, and the anchored section 40 of the frame member 37 is in the form of an angle seated in the groove 18 and secured by nails X to the frame 12 under the parting strip 16. The anchored section and the folded section of the frame member 37 have overlapping sliding contact, the latter with the former, that affords the slip joint 41 heretofore referred to. Obviously, the fold 39 is self-adjusting and permits lateral movement of the sash 19 in its runway 14 and the slip joint 41 permits horizontal movement of said sash in the plane thereof.

In the construction shown in Fig. 4 the sash member and frame member are designated, respectively, by the numerals 42 and 43 and said sash member is substantially like that shown in Fig. 1 except that the interlocked elements are rectangular in cross-section and indicated by the numeral 44. The frame member 43 includes a U-shaped fold 45, an anchored section 46 and a slip joint 47 therebetween and like the slip joint shown in Fig. 3.

Fig. 5 shows a construction like that of Fig. 1 except that the frame member has a slip joint in place of a flexing section. In this construction the numeral 48 indicates the sash member, the numeral 49 the frame member and the numeral 50 indicates the interlocked elements between the members 48 and 49. The frame member 49 includes a U-shaped fold 50 which corresponds to the fold 28 and the anchored section thereof is two-ply and in the form of an angle, one flange of which rests on the bottom of the runway 14 and is secured by nails X to the frame 12. The plies of the other flange of the anchored section of the frame member

49 are separated and the free flange of the fold 50 works therebetween with a wiping fit to form a slip joint 51 in the frame member 49.

In Fig. 6 the sash and frame members and the interlocked elements are designated by the numerals 52, 53 and 54, respectively. The sash member 52 and interlocked elements 54 are the same, as shown in Fig. 1, the fold 55, slip joint 56 are the same as that shown in Fig. 4, and the attachment of the frame member 53 to the frame 12 is the same as that shown in Fig. 3.

Fig. 7 is a fragmentary perspective view of the top portion of the frame member 53 and it will be noted that the anchored section thereof is folded over the fold section 55 at 57 to prevent said fold section from following the sash section 52 when the window is raised. Said fold section 55 rests on the window sill and is thereby held when the sash member 52 is sliding therein during the closing of the sash 19.

While Fig. 7 illustrates certain parts in Fig. 6, similar means are employed in the other types shown, as for example, the anchored section 37 in Fig. 3, 43 in Fig. 4, 49 in Fig. 5, 59 in Fig. 8, and 60 in Fig. 9. Also while Fig. 7 shows the lower sash only, similar means are employed with the upper sash, the fold 57 being at the bottom and the fold section 55 being held by the head of the frame instead of the sill.

The structure shown in Fig. 8 is the same as that shown in Fig. 6 except as to the attachment of the frame member to the frame 12. In this structure the sash member and the frame member, the interlocked elements that connect the same, and the slip joint, are indicated, respectively, by the numerals 58 to 62, inclusive.

In Fig. 9 the structure is the same as that shown in Fig. 8 with the exception that the anchored section of the frame member is provided with a second fold which gives said member the required flexibility to permit lateral movement of the sash 19 in its runway 14. The numeral 58 indicates the sash member, 59 the interlocked elements and 60 the frame member which has three-U-shaped folds 61, 62 and 63. The fold 61 is formed with the respective interlocked element 59 and the folds 62 and 63 are formed with the anchored section of the frame member 60. The folds 61 and 62 are interlocked to form a slip joint 64 which serves the same purpose as the slip joint heretofore referred to and the fold 63 gives the required flexibility to the frame member 60 and permits lateral movement of the sash 19 in the runway 14.

Fig. 10 shows a structure substantially the same as that shown in Fig. 8 with the exception that the interlocked elements 63, which connect the sash member 64 and the frame member 65, are oval-shaped in cross-section.

and the major axis thereof is in the plane of the sash 19.

The structure shown in Fig. 11 is like that shown in Fig. 10 with the exception that the interlocked elements 66, which connect the sash member 67 and the frame member 68, are oval-shaped in cross-section with the major axis thereof extending transversely of the sash 19.

10 What I claim is:

1. A weather strip device comprising a pair of members, applicable the one to a sash and the other to a frame in which the sash is slidably mounted, said two members having interlocked elements that hold said members for common movement except relative longitudinal sliding movement, one of said members having a part that is substantially parallel to the sash and arranged to yield and permit a limited lateral movement of the sash in respect to the frame.

2. A weather strip device comprising a pair of members, applicable the one to a sash and the other to a frame in which the sash is slidably mounted, said two members having interlocked elements that hold said members for common movement except relative longitudinal sliding movement, the frame member having a part that is substantially parallel to the sash and arranged to yield and permit a limited lateral movement of the sash in respect to the frame.

3. A weather strip device comprising a pair of members, applicable the one to a sash and the other to a frame in which the sash is slidably mounted, said two members having interlocked elements that hold said members for common movement except relative longitudinal sliding movement, the frame member having a U-shaped fold that extends substantially parallel to the sash and arranged to yield and permit a limited lateral movement of the sash in respect to the frame.

4. A weather strip device comprising a pair of members, applicable the one to a sash and the other to a frame in which the sash is slidably mounted, said two members having interlocked elements that hold said members for common movement except relative longitudinal sliding movement, one of said members having a part that is substantially parallel to the sash and arranged to yield and permit a limited movement of the sash both transversely of the frame and horizontally in the plane thereof.

5. A weather strip device comprising a pair of members, applicable the one to a sash and the other to a frame in which the sash is slidably mounted, said two members having interlocked elements that hold said members for common movement except relative longitudinal sliding movement, the frame member having two folds, one of which is substantially parallel to the sash and the other of which is substantially perpendicular to the plane

thereof, said frame member being arranged to yield and permit movements of the sash both transversely of the frame and horizontally in the plane thereof.

6. The structure defined in claim 1 in which one of said members is provided with a slip joint constructed and arranged to permit a limited horizontal movement of the sash in the plane of the frame.

7. The structure defined in claim 1 in which the frame member is provided with a slip joint constructed and arranged to permit a limited horizontal movement of the sash in the plane of the frame.

In testimony whereof I affix my signature.

FRANK REESE.
